(57) **CLAIM**

The ornamental design for a wall footer, as shown and described.

DESCRIPTION

FIG. 1 is a top plan view of the first embodiment of my design a wall footer.

FIG. 2 is a left side elevational view of the wall footer shown in FIG. 1.

FIG. 3 is a right side elevational view of the wall footer shown in FIG. 1.

FIG. 4 is an inverted bottom view of the wall footer shown in FIG. 1.

FIG. 5 is a left side elevational view of the wall footer shown in FIG. 4.

FIG. 6 is a right side elevational view of the wall footer shown in FIG. 4.

FIG. 7 is a top perspective view of the wall footer shown in FIG. 1.

FIG. 8 is a bottom perspective view of the wall footer shown in FIG. 1.

FIG. 9 is a top plan view of the second embodiment of my design a wall footer.

FIG. 10 is a left side elevational view of the wall footer shown in FIG. 9.

FIG. 11 is a right side elevational view of the wall footer shown in FIG. 9.

FIG. 12 is an inverted bottom view of the wall footer shown in FIG. 9.

FIG. 13 is a left side elevational view of the wall footer shown in FIG. 12.

FIG. 14 is a right side elevational view of the wall footer shown in FIG. 12.

FIG. 15 is a top perspective view of the wall footer shown in FIG. 9; and,

FIG. 16 is a bottom perspective view of the wall footer shown in FIG. 9.

The disc projections are repeated at regular intervals throughout the length of the wall footer.

The cut away portion in the drawings indicates the appearance of any portion of the wall footer between the cut away lines forms no part of the claimed design.
